DESIGN FOR AN EMBROIDERED LACE FABRIC

Jack Wiener, New York, N. Y.

Application July 25, 1942, Serial No. 107,680

Term of patent 3½ years

To all whom it may concern:

Be it known that I, Jack Wiener, a citizen of the United States of America, residing in New York city, county of New York, and State of New York, have invented a new, original, and ornamental Design for an Embroidered Lace Fabric, of which the following is a specification, reference being had to the accompanying drawing, forming part thereof.

The figure on the drawing is a plan view of an embroidered lace fabric showing my new design.

I claim:

The ornamental design for an embroidered lace fabric, substantially as shown.

JACK WIENER.
